UNITED STATES PATENT OFFICE.

EDWARD F. GAVIN, OF NEW YORK, N. Y.

ELECTRIC-LIGHTING SYSTEM.

SPECIFICATION forming part of Letters Patent No. 544,084, dated August 6, 1895.

Application filed September 28, 1894. Serial No. 524,384. (No model.)

To all whom it may concern:

Be it known that I, EDWARD F. GAVIN, a citizen of the United States of America, and a resident of the city of New York, in the 5 county and State of New York, have invented new and useful Improvements in Electrically-Illuminated Signs and the Like, of which the following is a specification.

This invention relates to illuminated advertising-signs, and more especially to that class 10 of such signs in which the illumination is secured by means of incandescent electric lamps, and wherein each letter or character consists of a frame or letter-form of proper 15 shape and a plurality of lamps disposed along the same in a manner to form illuminated lines or masses corresponding in shape with the letter-forms.

The object of the invention is to produce 20 an illuminated sign which is durable in character, capable of withstanding rain and moisture when used out of doors, and which shall be cheap to manufacture and economical in use.

The invention consists in the matter here- 25 after described, and pointed out in the appended claims.

In the accompanying drawings, illustrating 30 my invention, Figure 1 is a view in front elevation of a single letter constructed in accordance with my invention. Fig. 2 is a side or edge view thereof. Fig. 3 is an enlarged section through one of the lamp-sockets and its attaching devices. Fig. 4 is a detail face view of the socket-holding device on the letter-form. Fig. 5 is a detail face view of the end 35 of the socket which engages the said socket-holding device. Fig. 6 is a detail rear view of a part of the letter-form, showing the arrangement of wires thereon.

As shown in said drawings, A indicates a 40 letter-form or frame made in the shape of a letter; B, electric incandescent lamps or lamp-bulbs, and C, sockets for the same. The lamp-sockets C are attached at their 45 open ends to the letter-form, so as to project from the reverse or rear face of said letter-form, while the lamp-bulbs are located at the front face of the form, which latter is provided with holes or apertures a a opposite 50 the sockets, through which holes the stems of

the lamp-bulbs are inserted, this construction bringing the body of the bulb or the carbon filament thereof close to the face of the letter-form.

The letter-form A is adapted for attachment 55 with other similar letter-forms to the supporting-framework or sign-body in the same manner as in similar signs heretofore made.

The attachment of the letter-forms to the 60 sign-body may be effected in any desired manner, and as the construction of the sign-body constitutes no part of the present invention it is not herein described nor shown. The said letter-forms may be made of any 65 desired material; but to secure cheapness and economy of construction I prefer to make them of wood and of uniform thickness throughout. The wooden forms may be readily constructed by joining flat strips or boards; 70 but they may be constructed in any manner desired. The wooden forms I prefer to paint or cover with a waterproof or a water and fireproof composition such as is used for insulating purposes.

The lamp-sockets C are in their main features similar to those heretofore used in incandescent-electric lighting to receive and hold the glass bulb or lamp proper, said sockets consisting generally of cylindric bodies 80 closed at one end and provided with separate interior contact-pieces adapted for contact with similar contact-pieces on the bulb when the latter is inserted in the socket. Said sockets differ, however, from those heretofore 85 used for illuminated signs in being adapted for detachable connection with the letter-form instead of being permanently secured thereto. To provide for such detachable connection, fastening means are employed whereby the 90 socket may be readily attached to and detached from the letter-form, and the said letter-form is provided with contact-pieces in electric connection with supply and return wires trained along and secured to the letter-form, which contact-pieces are adapted to 95 make contact with other similar contact-pieces on the outer or open ends of the sockets when the latter are secured in place on the form. The lamp-sockets are thus made 100

entirely detachable from the letter-form without disturbing the wires, which latter are permanently attached to the letter-form.

To now refer more specifically to the details of construction illustrated in the lamp-sockets and means for securing the same to the letter-form, these parts are made as follows: D indicates a ring of insulating material, which is secured directly to the letter-form, so as to surround the hole a therein, and which serves to immediately engage and support the socket. Said ring D has attached to it the contact-pieces E F, through the medium of which the current is transmitted to the socket and lamp. The socket C is adapted to fit within the ring D and is provided with contact-pieces G H, located in such position relatively to the contact-pieces E and F that those on the socket will come opposite those on the ring when the socket is inserted in the ring. The contact-pieces E and F on the ring are connected with the supply and return wires I and J of the letter-form, the terminals i j of such wires being led from the body of the material composing the ring in the manner clearly shown in Fig. 3. Similarly the contact-pieces G and H of the socket are connected with a screw-threaded tube c and plug c' , which form the interior contact-pieces of the socket by means of connecting-wires g h , extending through the insulating material of the socket. The socket illustrated consists of a single mass of insulating material, such as hard rubber or a combination of mica and shellac, in which the several contact-pieces c , c' , G, and H are embedded. Similarly the ring D preferably consists of a single mass of insulating material having embedded in its side wall the contact-pieces E and F.

I prefer to construct the contact-pieces E and F of the ring D and G and H of the socket C in such manner that they may be interlocked with each other, and thus constitute the fastening device for holding the socket in place within the ring as well as contact-pieces for making electric connection between the lamp and wires. For the purpose stated, these parts are constructed as follows: The inner surface of said ring D, within which the end of the socket is adapted to fit, is cylindric, as indicated at d , Figs. 3 and 4, and the contact-pieces E and F are made segmental in form and are secured in said cylindric surface at opposite sides of the ring. The socket C is provided with an exterior cylindric surface c^2 corresponding with the surface d , and the contact-pieces G H thereof are similarly made of segmental shape and attached to said cylindric surface at opposite points on the same. The several contact-pieces E F and G H are provided with interfitting ribs or projections, which are inclined so as to form partial screw-threads, the contact-pieces being made of

length less than a quarter of the circumference of the ring, so that when the contact-pieces of the socket are placed opposite the spaces between the contact-pieces of the ring the socket may be thrust into the ring, and thereafter turned to bring the ribs or screw-threads of the two sets of contact-pieces into engagement with each other. The ribbed or screw-threaded contact-pieces described may most conveniently be made of sheet-metal bent or stamped into corrugated form, as heretofore, and may be secured to the insulating material of the socket-ring by means of integral projections, which are indicated by dotted lines at the ends of the contact-pieces in Figs. 4 and 5.

In order to prevent access of water or moisture to the contact-pieces, I provide opposing surfaces or shoulders on the ring and socket at either side of the contact-pieces, and between said opposing surfaces or shoulders I place packing-rings K L of rubber or other suitable material. In the particular construction herein shown the packing-ring K is located between a flange c^2 on the socket and the outer face of the ring D, while the packing-ring L is located between an inwardly-projecting flange d' on the ring D and the end surface of the socket.

The ring D is shown as seated in an annular recess or rabbet a' , which surrounds the hole a at the inner or rear face of the letter-form. The rear face of the ring is preferably made flush or nearly so with the rear surface of the letter-form, so that the thickness of the latter is not materially increased at the point where the socket is secured to the same. The said ring D may be secured within the rabbet a' by any suitable form of fastening device, and in cases where it is preferred to have the rings readily detachable or removable a fastening device proper for the purpose, such as a turn-button, may be employed. Ordinarily, however, attachment by means of screws inserted through the ring and into the body of the letter-form will be sufficient. In order to provide a suitable place for the insertion of holding-screws, and also to permit the passage of the wires from the ring at points outside of the socket, I provide the said ring, at its inner side, with a flange projection d^2 , which fits within a secondary rabbet a^2 in the letter-form. In the construction illustrated, ordinary wood-screws d^3 d^4 , Fig. 4, inserted through the flange d^2 and into the wood beneath said flange, serve to secure the ring in place within the rabbet.

I prefer to make the opening a in the letter-form smaller than the interior opening of the ring D and large enough only to admit the passage of the bulb-stem, this construction being employed to avoid the presence of an opening around the lamp, which would give an unsightly appearance to the letter, especially where the same is painted of a white

color or some light color in order to reflect the light and to improve the appearance of the sign.

Between the several rings D D the wires I 5 and J will be stretched along the surface of the letter-form and properly secured to the same. The wires between adjacent rings will be made only long enough to allow the rings to be easily handled in fastening them to the 10 form, so that there will be practically no surplus wire and no waste. The wire being fastened against the letter-form between the rings, the rear surface of the letter will present a practically smooth and uniform appearance, thereby avoiding the presence of unsightly loops or coils of wire at the rear surface of the letter-form.

In the manufacture of letter-forms constructed as described the forms will usually 20 be made and the rings and wires attached thereto by the manufacturer, so that the frame properly wired will be in readiness to be secured in place as part of the sign, while the lamps and lamp-sockets will be supplied in 25 suitable quantities as needed for use. In order, therefore, to be able to supply any needed words or characters, it will be necessary for the manufacturer or dealer in such signs to carry in stock or have on hand enough lamps 30 and sockets only to supply the letter-forms used in such words as may be called for, it being of course necessary to keep on hand full sets of letter-forms in order to be able to supply any word or words needed. Considerable economy in the cost of sockets required 35 for carrying on business, especially where the letters are not sold, but leased for use, is thus secured, the sockets being the most expensive parts required for the signs.

40 In the case of signs in which the lamp-sockets are permanently attached to the letter-forms, as heretofore made, and in which the supply and return wires extend from socket to socket and are permanently connected with 45 the sockets, the letter-forms, sockets, and wires necessarily constitute integral and permanent structures. With the use of such devices, therefore, a complete set of letters must be made for each sign called for, and in case 50 one person desires to be prepared to furnish signs either by sale or rental he must keep on hand a complete set of letters, corresponding with a font of type, from which letters to form any desired word may be selected. This necessarily involves the investment of a large 55 amount of capital, a considerable part of which is employed to supply the needed sockets for all the letters. In a sign embodying my improvements, in which the lamp-sockets are 60 made detachable from the letter-forms, the number of sockets necessary to be kept on hand under the circumstances stated need be equal only to the number required for supplying the letter-forms which at any one time 65 may be in actual use, while the cheaper parts—namely, the letter-forms—may be kept on

hand in number and variety sufficient to make any desired sign at a relatively smaller expense. This advantage is especially obvious in the case of theatrical signs, for the 70 reason that these are commonly changed to correspond with the names of the plays placed on the boards. In the use of letters made as proposed by me the owner or manager of the theater may have a set of letter-forms covering one or more alphabets, so that any desired name or title may be supplied therefrom; but he need have on hand a number of lamp-sockets and lamps sufficient only to supply a sign of the usual size. 80

In addition to the main features of construction hereinbefore referred to, by which the lamp-sockets are made detachable from the letter-forms, and the letter-forms and sockets are provided with contact-pieces, as 85 described, some of the minor features of construction illustrated and hereinbefore set forth also constitute important parts of my invention.

While I have hereinbefore referred to the 90 use of my improvements as applied to the manufacture of signs only, it will be understood that they may be employed with equal advantage wherever it is desired to employ incandescent electric lamps in numbers for 95 the purpose of ornamentation or display, as well as for illumination—as, for instance, in applying incandescent lamps for the decoration of buildings strips of any length and shape corresponding with the strips employed 100 in making the letter-forms may obviously be used for supporting sockets and attaching devices in the same manner as hereinbefore set forth.

Important advantages are obtained by providing the letter-forms with holes for the bulb-stems and attaching to the rear face of the letter-forms lamp-sockets, which are closed at their rear ends in such manner as to project rearwardly from the said letter-forms, so that 110 the bulb-stems extend through the letter-support and the bulbs are brought close to the outer surface of the sign, not only because the letter is by this construction given a bright, clean, and uniform appearance not possessed 115 by signs in which the lamps extend their full length from the face of the lamp-support, but also because the construction of the letter is greatly simplified by reason of the absence of any supporting devices for the sockets at 120 the rear of the letter-form, while at the same time the conductors and sockets are protected from moisture, and the structure as a whole is light in weight and may be easily and cheaply made. 125

I claim as my invention—

1. An illuminated sign or ornament, comprising a letter-form or like lamp support provided with a plurality of sets of insulated contact pieces, a plurality of lamp sockets 130 detachably secured thereto, said lamp sockets being provided with insulated contact pieces

- for engagement with the contact pieces of the bulb stems, and also with contact pieces for engagement with the insulated contact pieces on the lamp support, and conducting wires extending along the lamp support and permanently connected with the said insulated contact pieces on said support, substantially as described.
2. An illuminated sign or ornament comprising a letter-form or like lamp support, provided with insulated contact pieces, a plurality of lamp sockets detachably connected with the lamp support and provided with contact pieces for engagement with the contact pieces on the bulb stems, and also with contact pieces for engagement with the contact pieces on the lamp support, and conducting wires extending along and secured to the rear face of the lamp support, said wires being permanently connected with the insulated contact pieces on said lamp support, substantially as described.
3. The combination, with a letter form or other lamp-support adapted to hold a plurality of lamps, the same being provided with a plurality of holes for the bulb-stems, of lamp sockets which are closed at their rear ends to exclude moisture and are sustained by attachment at their front or open ends to the lamp-support, said sockets being located at the rear face of the same, opposite said holes and projecting rearwardly from the lamp-support, so as to bring the lamp-bulbs near the front face thereof, substantially as described.
4. The combination, with a letter form or other lamp-support adapted to hold a plurality of lamps, the same being provided with a plurality of holes for the bulb-stems, of lamp sockets which are closed at their rear ends to exclude moisture and are sustained by attachment at their front or open ends to the lamp-support, said sockets being located at the rear face of the same opposite said holes and projecting rearwardly from the lamp support, and conducting wires extending along the rear-face of the support and connected with the contact pieces of the sockets, substantially as described.
5. The combination with a letter form or other lamp-support provided with holes for the bulb-stems, sockets detachably secured to the lamp-support and projecting from the rear face thereof, and insulated contact pieces on the lamp-support and sockets adapted for engagement with each other when the sockets are secured to the lamp-support, substantially as described.
6. The combination with a letter form or other lamp-support, provided with holes for the bulb-stems of rings of insulating material attached to the lamp-support sockets having detachable connection with said rings, and contact pieces on the rings and sockets, substantially as described.
7. The combination with a letter form or other lamp-support, provided with holes for the bulb-stems of lamp-sockets and rings of insulating material attached to the lamp-support, said rings and the sockets being provided with interlocking parts and with contact pieces, substantially as described.
8. The combination with a letter form or other lamp-support provided with holes for the bulb-stems, of rings of insulating material attached to the lamp-support, lamp-sockets having detachable connection with the rings, contact pieces on the rings and sockets and conducting wires extending along the rear surface of the lamp-support and connected with the contact pieces of the rings substantially as described.
9. The combination with a letter form or other lamp-support provided with holes for the bulb-stems of rings of insulating material attached to the lamp-support sockets detachably secured to the rings, contact pieces on the rings and sockets and wires extending along the rear surface of the lamp-support and passing through the insulating material of the rings to the contact pieces thereon, substantially as described.
10. The combination with a letter form or other lamp-support provided with holes for the bulb-stems, of rings of insulating material attached to the lamp-support, sockets adapted to engage the said rings, and metal contact pieces on the rings and sockets, provided with interlocking parts for holding the sockets in engagement with the rings, substantially as described.
11. The combination with a letter form or other lamp-support, provided with holes for the bulb-stems, of lamp-sockets detachably secured to the said lamp-support, contact pieces on the lamp-support and sockets, and means for packing the joints between opposing surfaces of the socket and lamp-support at either side of the contact pieces to exclude moisture from the same, substantially as described.
12. The combination with a letter form or other lamp-support, of a ring of insulating material secured to the lamp-support, a lamp-socket detachably engaged with the said ring, contact pieces on the socket and ring, and means for packing the joints between opposing surfaces of the ring and socket at either side of the contact pieces to exclude moisture from the said contact pieces, substantially as described.
13. The combination with a letter form or other lamp-support provided with holes for the bulb-stems, rings of insulating material seated in rabbets surrounding the holes, sockets detachably secured to the rings, and contact pieces on the rings and sockets, substantially as described.
14. The combination with an apertured letter form or other lamp-support, of a ring of

insulating material having contact pieces embedded therein, and a socket detachably secured to the ring, and also made of insulating material having contact pieces embedded therein, substantially as described.

15. The combination with an apertured letter-form or other lamp-support, of a detachable lamp-socket, said support and lamp-socket being provided with oppositely arranged, insulated, segmental, contact plates provided with inclined ribs or screw threads

adapted to be interlocked by rotary motion of the socket, substantially as described.

In testimony that I claim the foregoing as my invention I have signed my name, in presence of two witnesses, this 21st day of September, 1894.

EDWARD F. GAVIN.
